UNITED STATES PATENT OFFICE.

WILHELM SCHWALGE, OF ELMHURST, ILLINOIS.

INCUBATOR.

1,187,934.

Specification of Letters Patent. Patented June 20, 1916.

Application filed July 24, 1913. Serial No. 780,899.

To all whom it may concern:

Be it known that I, WILHELM SCHWALGE, a citizen of the United States, residing at Elmhurst, in the county of DuPage and 5 State of Illinois, have invented certain new and useful Improvements in Incubators, of which the following is a specification.

The essential object of this invention is to provide an incubator having a plurality 10 of separate and independent compartments and provided with devices by which the heat in each compartment is regulated independently of the others.

In the drawings, Figure 1 is a perspective view of an incubator equipped with the invention; Fig. 2 is a top plan view of the incubator, the cover being removed; Figs. 3 and 4 are views at right angles to each other of the main heat-distributing pipe; 20 and Fig. 5 is a detailed sectional view of part of one of the pipes together with its regulating mechanism.

The incubator comprises a suitable casing 1 supported upon legs 2 and having cover 25 3. As best shown in Figs. 1 and 2 the casing 1 is divided into a plurality of compartments 4 by means of partitions 6. Each compartment has its own door or doors and the trays 8 of eggs can be placed in the appropriate compartment. The primary reason 30 for dividing the incubator into compartments is to permit inspection of the contents of each or any compartment without permitting the escape of the warm air from any other compartment. More specifically, if it 35 becomes necessary to open the particular door 7 which is shown as being open in Fig. 1, either for the purpose of changing the trays or for any other reason, it is not necessary 40 to open any of the other compartments, and since from time to time each of the compartments will in the ordinary course of operation be opened and its temperature reduced below the temperature of the remaining 45 compartments, it is one of the features of this invention to control the temperature of each compartment independently of the other compartments.

The heat is supplied from a suitable 50 burner 10 which may conveniently be an ordinary oil lamp. Above the chimney 11 of the lamp is the drum 12, provided with a hood 13 adapted to direct the heat inside the drum. The top of the drum is open as 55 at 13^a and can be closed by the valve 14, which is controlled by the movable support

15: A pipe 16 extends from the drum 12 to the box 17, and within the box there is a thermostat, not shown, or similar device for controlling the hanger 15, and causing 60 the same automatically to rise when the temperature within the box 17 passes beyond a predetermined point. When the parts are as shown in Figs. 1 and 3, the open end of the drum 12 will permit the 65 escape into the outer atmosphere of the heat from the lamp; but when the valve 14 is seated upon the drum, the opening will be closed and the heat will be forced from the drum from whence it will pass into and 70 through pipes 16 and 18. That heat passing through pipe 16 and into the box 17 will control the thermostat within the box, causing the valve 14 to open when the temperature becomes high and to close when the 75 temperature becomes low.

The pipe 18 is surrounded by a pipe 19 which is somewhat larger in diameter than pipe 18 and which extends practically from one end to the other of the casing 1. It is 80 from pipe 19 that the warm air is distributed to the different compartments of the incubator. In order to effect this distribution, pipe 19 is provided with as many nipples 20 as there are compartments. Each 85 nipple 20 is in communication with a pipe or conduit 21, each of said conduits 21 being divided into two branches, and adjacent each end of each branch of the conduit 21 are conduits 22, each of which extends outwardly from the conduit 21 and substantially at right angles thereto, then extends parallel to the conduit 21 and toward the center of the incubator, and then upwardly through the top or cover 3, the mouth or 90 discharge end of each conduit 22 being a short distance above the top of the cover. The heated gases from the pipe 19, therefore, pass upwardly through the nipples 20, thence horizontally through the pipes 21, 95 and thence escape into the atmosphere after having passed through the conduits 22. The heated gases, accordingly, are not discharged directly into the compartments of the incubator but warm or heat the same as 100 they pass through the pipes 19, 21, and 22.

In order to shut off the heated gases from any compartment when the temperature in that compartment has reached a predetermined point, the device, best shown in Fig. 110 5, is applied. From said figure it will be seen that the conduits 21 communicate with

the nipples 20 through a chamber 24. Said chamber 24 is perforated at 25 so as to permit the heated gases to enter the chamber 24 from the nipple 20, and is also perforated at 26 through which perforations 26 the heated gases escape from the chamber 24 into the conduits 21. Each perforation 26 is controlled by a valve 28 carried upon a stem 28^a, and the stems 28^a, in turn, 10 are secured to the pivoted and counter-weighted levers 29. Thermostats 30 which project through the cover 3 and into the respective compartments control said levers 29 and are so constructed that when the 15 temperature in any compartment rises above a predetermined point, the thermostat 30 will expand, thus forcing the valve 27 downwardly so as to close the appropriate opening 26, which closing of the valve, obviously, prevents further flow of the heated 20 gases into that pipe or pipes 21 and 22 which enter such compartment. As clearly shown in the drawings, there is a branch 25 of conduit 21 on each side of the main supply pipe 19, and in order more certainly to control the apparatus there is a separate lever 29, valve 28, and thermostat 30 for each branch of the conduit 21.

In order to permit the heated gases to pass 30 from the pipe 18 into the surrounding pipe 19, said pipe 18 is provided with perforations 35, 36 and 37, as best shown in Fig. 4. The perforation 35 which is nearest to the heater 10 is relatively small in diameter; the 35 perforation 36 is larger than the perforation 35; the perforation 37 is larger than the perforation 36, and so on, it being desirable to increase the size of the perforations in the pipe 18 according to the increase in the distance of such perforations from the heater. In this manner, each of the several compartments of the incubator will receive the same 40 number of units of heat as any other compartment. Were the perforations 35, 36 and 45 37 each of the same size, the particular compartment or compartments which are fed or supplied with heated air through perforation 35 would become heated sooner than the compartment or compartments supplied 50 through the perforation 37 for, obviously the heated gases will travel along the line of the least resistance, and were the perforations to be of equal size, the heated gases 55 would tend to pass into the compartment nearest the heater rather than to force their way through into the compartments which are farthest removed from the heater. By 60 making the passage of the heated gases from the pipe 18 to the first compartments relatively difficult (because of the provision of a relatively small passageway) and by making the passage of the heated gases from the same pipe into the compartments farthest removed from the incubator relatively easy 65 (by providing a large passageway), and by

properly proportioning the sizes of the passageways, it is obvious that the heat is uniform in the different compartments, regardless of their distance from the incubator. This arrangement of the sizes of the 70 passageways through which the heated gases pass into any particular compartment, tends to an equal distribution of the heated gases to pipe 19 longitudinally thereof.

The operation of the incubator will be 75 clearly evident from the foregoing detailed description of parts, and no particular description of the operation is deemed necessary further than to direct attention to the fact that the pipes 19, 21, and 22 are so arranged as to reach and warm the compartment within which they are respectively placed both in the middle, at the ends and along the sides. It will be obvious further 80 that numerous changes in the arrangement 85 of details and construction of parts may be made without departing from the scope of the invention.

I claim as my invention:

1. A multiple compartment incubator 90 comprising a plurality of separate compartments arranged in two longitudinal horizontal rows and transverse pairs, a main longitudinal horizontal supply pipe extending through the incubator between the rows, a plurality of transverse horizontal conduits disposed in separated arrangement above the horizontal plane of the supply pipe, and each having its opposite ends extending within the two compartments of the pair which it 95 heats, an individual angular heat distributing means located within each compartment and connected to the end of the transverse conduit extending thereon, vertical connections between said conduits and the 100 supply pipe, and an air admission controlling means centrally located in each conduit over the upper termination of its vertical connection.

2. A multiple compartment incubator, 110 comprising a plurality of separate compartments arranged in two longitudinal horizontal rows and transverse pairs, a main longitudinal horizontal supply pipe extending through the incubator between the rows, a 115 plurality of transverse horizontal conduits disposed in separated arrangements above the horizontal plane of the supply pipe and each having its opposite ends extending within the compartments of the pair which it heats, a plurality of approximately U-shaped pipes, 120 each located within one of the compartments and connected to the outer end of the transverse horizontal conduit, vertical connections between said transverse horizontal conduits and the supply pipe and an air admission controlling means centrally located in each transverse horizontal conduit over the upper termination of its vertical connection.

3. A multiple compartment incubator, 125

- comprising a plurality of separate compartments arranged in two longitudinal horizontal rows and transverse pairs, a main longitudinal horizontal supply pipe extending 5 through the incubator between the rows, a plurality of transverse horizontal conduits disposed in separated arrangement above the horizontal plane of the supply pipe and each having its opposite ends extending 10 within the two compartments of the pair which it heats, a plurality of approximately U-shaped pipes, each located within one of the compartments in horizontal position therein and connected at the center of its 15 medial member to the outer end of the conduit and the two end members thereof extending parallel with the conduit, vertical connections between said conduits and the supply pipe, and an air admission control- 20 ling means centrally located in each conduit over the upper termination of its vertical connection.
4. An incubator comprising a plurality of compartments arranged in longitudinal horizontal rows and transverse pairs, a supply pipe extending longitudinally and horizontally through the incubator, there being a 25 row of compartments upon each side of said supply pipe, a transverse horizontal conduit extending between and connecting the compartments of each pair, said conduit being located above the horizontal plane of the supply pipe and being connected at its 30 middle to said supply pipe, a second conduit of angular form extending from the first mentioned conduit through the compartment, and having its ends extending into the outer atmosphere, and means for controlling the 35 passage of air from said supply pipe into each of said conduits.
5. An incubator comprising a hot air supply pipe extending longitudinally and horizontally through the incubator, a plurality of compartments arranged in longitudinal horizontal rows on opposite sides of said supply pipe, a plurality of transverse horizontal conduits connecting said compartments in transverse pairs, said conduits being located 45 above the horizontal plane of the supply pipe and being connected at their centers to said supply pipe, a second plurality of conduits each of which is located within one of the compartments and connected to one of said first mentioned conduits each being of U-shaped form with its opposite ends extending through the wall of the compartment, and opening into the outer atmosphere, and means for controlling the passage of air from said supply pipe into said first mentioned conduit. 55
6. An incubator comprising a plurality of compartments in two separated longitudinal horizontal rows, a horizontal supply pipe extending centrally between the longitudinal rows and in juxtaposition to each of said compartments, a horizontal main heat-distributing pipe of large circumference surrounding said supply pipe, a plurality of transverse horizontal conduits in separated arrangement, each connected at its middle 60 to the distributing pipe and having its ends extending within and connecting opposite compartments of the two longitudinal horizontal rows in a transverse pair, and passageways connecting said distributing pipe 65 and said supply pipe, and an individual heat distributing pipe in each compartment connected to the end of the conduit. 70
7. An incubator, comprising a plurality of compartments in longitudinal horizontal rows, a horizontal supply pipe extending in juxtaposition to each of said compartments, a main heat-distributing pipe surrounding said supply pipe, passageways connecting said distributing pipe and said supply 75 pipe, and a plurality of centrally arranged transverse horizontal conduits extending from said distributing pipe and having their ends extending into and connecting said compartments in trans- 80 verse pairs, said conduits being disposed above the horizontal plane of the supply pipe, and an angular individual heat distributing pipe in each compartment connected to the end of the transverse conduit. 85
- In testimony whereof I hereunto affix my signature in the presence of two witnesses.
